US0D1034300S

(12) **United States Design Patent** (10) **Patent No.:** **US D1,034,300 S**
(45) **Date of Patent:** ** *Jul. 9, 2024

(54) **SNAP FASTENER**

(71) Applicant: **Fidlock GmbH**, Hannover (DE)

(72) Inventor: **David Richter**, Hannover (DE)

(73) Assignee: **FIDLOCK GMBH**, Hannover (DE)

(*) Notice: This patent is subject to a terminal disclaimer.

(**) Term: **15 Years**

(21) Appl. No.: **29/790,147**

(22) Filed: **Nov. 9, 2021**

(30) **Foreign Application Priority Data**

May 20, 2021 (DE) 402021100477.7

(51) **LOC (14) Cl.** **02-07**

(52) **U.S. Cl.**

USPC **D11/220**

(57) **CLAIM**

The ornamental design for a snap fastener, as shown and described.

DESCRIPTION

FIG. 1 is a top perspective view of a snap fastener, showing the new design;

FIG. 2 is a top plan view thereof;

FIG. 3 is a bottom plan view thereof;

FIG. 4 is a right side view thereof;

FIG. 5 is a left side view thereof;

FIG. 6 is a front view thereof; and,

FIG. 7 is a rear view thereof.

Broken lines depict portions of the snap fastener which form no part of the claimed design.

1 Claim, 7 Drawing Sheets
